UNITED STATES PATENT OFFICE.

SALVATORE FERRAGAMO, OF SANTA BARBARA, CALIFORNIA.

TURNUCKLE.

1,413,328.

Specification of Letters Patent. Patented Apr. 18, 1922.

Original application filed February 4, 1921, Serial No. 442,469. Divided and this application filed June 22, 1921. Serial No. 479,474.

To all whom it may concern:

Be it known that I, SALVATORE FERRAGAMO, a subject of the King of Italy, residing at Santa Barbara, in the county of Santa Barbara and State of California, have invented certain new and useful Improvements in Turnbuckles; and I do hereby declare the following to be a full, clear, and exact description of the invention, such as will enable others skilled in the art to which it appertains to make and use the same.

This invention relates to turnbuckles of a type disclosed in an application filed by me February 4, 1921, Serial Number 442,469, of which this is a divisional application.

An object of the present invention is to provide means including a detachable operating device for facilitating the easy manipulation of the turnbuckle.

Another object is to produce a turnbuckle having a detachable operating handle capable of being readily positioned upon the yoke or frame and formed with radially projecting arms which provide for the free and easy rotation of the said yoke when moving the screw.

Other objects will in part be obvious, the invention consisting in the construction and arrangement of the turnbuckle as will more fully hereinafter appear and be pointed out in the appended claims.

In the accompanying drawings wherein similar reference characters designate corresponding parts in the several views,

Figure 1 is a view in side elevation of my improved turnbuckle partly in section;

Figure 2 is a transverse sectional view on the line 2—2 of Figure 1; and

Figure 3 is a detail face view partly in section of the detachable spider or ring-like frame to which the operating arms are secured.

Referring to the drawings, the turnbuckle is shown as comprising a supporting frame or yoke 1 formed of parallel side bars 2 united at their respective ends as at 3 to form bearing supports for the screws 4. Engaging devices in the form of open links or hooks 5 are provided on each screw to permit of the connecting or interpositioning of the turnbuckle. A single screw may be used instead of the double construction shown and various other forms of engaging devices may be employed as will be understood.

The operating device is positioned upon the supporting frame of the turnbuckle and comprises an encircling spider or ring-like member 6 provided with a series of radially projecting arms 7. Each arm is preferably provided with a shank 8 adapted to be fitted in an opening 9 and riveted over as shown at 10. These arms may be attached to the spider in other ways, or they may be cast integral therewith if desired.

Recesses or cut-away portions 11 are formed in the spider 6 and are arranged to fit upon squared portions 12 provided on the longitudinal arms of the turnbuckle. It is desirable to make a sliding and relatively snug fit whereby the operating device can be easily positioned upon the turnbuckle and at the same time remain in its fitted position thereon. A set screw 13 may be used to hold the supporting spider in place whereby all tendency of the operating device to slide off the portion 12 when the turnbuckle is used in other than horizontal positions, is obviated.

When assembling, the spider or ring-like member is slipped over the end of the turnbuckle and the recessed portions 11 are fitted upon the surfaces 19. The set screw is now inserted and to all intents and purposes the operating device becomes an associated part of the turnbuckle. When desired the operating device can be quickly detached by removing the screw 13 and sliding the ring member off the turnbuckle. This is advantageous when shipping or storing the turnbuckle as will be understood.

The uses to which my improved turnbuckle may be applied are many and I do not limit its application to any particular apparatus, but for example I have found it particularly useful in connection with a surgical apparatus set forth in an application bearing Serial Number 427,740, filed by me December 2, 1920.

I claim:

1. A turnbuckle comprising a supporting or connecting frame, an engaging device carried by said frame, means for permitting the relative movement of said frame and engaging device, and an operating handle 105 slidably fitted upon the frame for rotating the turnbuckle, said operating handle being detachably associated with said frame and having a projecting arm.

2. A turnbuckle comprising a supporting 110

frame, engaging devices carried by said turnbuckle, means for moving the engaging devices with relation to the supporting frame, and an operating handle for rotating 5 the supporting frame, said handle including an encircling member slidably positioned upon the frame intermediate the ends thereof, and provided with a projecting arm.

3. A turnbuckle comprising a supporting 10 frame, engaging devices carried by said turnbuckle, means for moving the engaging devices with relation to the supporting frame, and an operating device for rotating the supporting frame, said device including 15 a member detachably associated with the supporting frame intermediate the ends thereof and provided with a series of projecting arms.

4. A turnbuckle comprising a supporting 20 frame, an engaging device carried by said turnbuckle, means for moving the engaging device with relation to the supporting frame, and an operating device detachably associated with the supporting frame intermediate the ends thereof. 25

5. A turnbuckle comprising a supporting frame, an engaging device carried by said turnbuckle, means for moving the engaging device with relation to the supporting 30 frame, an operating device adapted to be

slidably fitted upon the supporting frame, and means for detachably securing said operating device thereto.

6. A turnbuckle comprising a supporting frame, an engaging device carried by said turnbuckle, means for moving the engaging device with relation to the supporting frame, and a detachable operating handle formed with recesses for slidably engaging the supporting frame whereby the said supporting 35 40 frame is rotated for moving the aforesaid engaging device.

7. A turnbuckle comprising a supporting frame formed of longitudinal arms having squared surfaces thereon, engaging devices 45 carried by said turnbuckle, means for moving the engaging devices with relation to the supporting frame, and an operating handle provided with recesses adapted to engage the aforesaid squared surfaces of the longitudinal arms whereby the supporting frame is rotated for moving the aforesaid engaging devices.

In testimony whereof I affix my signature, in presence of two subscribing witnesses. 55

SALVATORE FERRAGAMO.
